CLAIM

The ornamental design for display with lightbar for vehicle guidance, as shown and described.

DESCRIPTION

FIG. 1 is a perspective view of a display with lightbar for vehicle guidance in accordance with the present invention; FIG. 2 is a top view thereof;

FIG. 3 is a bottom view thereof;

FIG. 4 is a left side view thereof;

FIG. 5 is a right side view thereof;

FIG. 6 is a rear view thereof;

FIG. 7 is a front view thereof;

FIG. 8 is a front view thereof and in a condition of use;

FIG. 9 is a front view thereof and in another condition of use;

FIG. 10 is a front view thereof and in another condition of use;

FIG. 11 is a front view thereof and in another condition of use;

FIG. 12 is a front view thereof and in another condition of use; and,

FIG. 13 is a front view thereof and in another condition of use.

The broken lines in the Figures show portions of the display with lightbar for vehicle guidance and environment which form no part of the claimed design.
